UNITED STATES PATENT OFFICE.

JOSEPH E. BOHNER, OF ANSONIA, CONNECTICUT, ASSIGNOR TO THE
WALLACE & SONS, OF SAME PLACE.

DESIGN FOR A TABLE-TOP FRAME.

SPECIFICATION forming part of Design No. 24,925, dated November 26, 1895.

Application filed October 8, 1895. Serial No. 565,083. Term of patent 8 $\frac{1}{2}$ years.

To all whom it may concern:

Be it known that I, JOSEPH E. BOHNER, a citizen of the United States, residing in Ansonia, in the county of New Haven and State 5 of Connecticut, have invented and produced a new and useful Design for Table-Top Frames, of which the following is a specification, reference being had to the accompanying drawing, which illustrates the design.

10 The design relates to a vertically-arranged band or frame for use beneath a table-top.

In the accompanying drawing the dotted lines represent a table-top and the table-legs, while the full lines show the frame and its 15 usual arrangement relatively to a table-top and the legs thereof.

The design of the border consists, generally, of the oval disks A, surrounded by conven-

tionalized leaf and shell like ornamentation B, and also of the vine-like scrolls C, reversely 20 arranged on opposite sides of the design A and B. This arrangement of scrolls and disks is repeated along the entire extent of the border. Various intermediately-arranged conventionalized flowers, scrolls, leaves, &c., as 25 shown, constitute detail parts of the border, together with band D.

The leading features of the design are those above indicated.

What is claimed as new is— 30

The design for a table top frame, substantially as shown and described.

JOSEPH E. BOHNER.
